UNITED STATES PATENT OFFICE

ANTHONY E. WEINGARTNER, OF PHILADELPHIA, PENNSYLVANIA, ASSIGNOR TO
AMERICAN ENGINEERING COMPANY, OF PHILADELPHIA, PENNSYLVANIA, A COR-
PORATION OF PENNSYLVANIA

GEARING FOR STOKERS

Application filed September 16, 1922. Serial No. 583,541.

This invention relates to mechanism especially adapted for transmitting power from a source such as a motor or driven shaft, to the rams or other reciprocating elements of 5 automatic stokers, particularly of the inclined underfeed type, and one object of said invention is to provide a relatively simple, substantial and compact spur-gear power-box for the above purpose, which shall possess a high efficiency and provide the required 10 gear reduction within a minimum space.

I further desire to provide a novel arrangement of spur gearing which in addition to being compact and substantial in construction, shall be in a large degree balanced so as to avoid objectionable lateral stresses upon its supporting structure;—the invention further contemplating a novel combination of planetary gearing, together with simple and 20 conveniently operated means whereby a driven element may be operated at any of several different speeds.

Another object of my invention is to provide a novel combination of power transmitting gearing especially adapted for the above purposes, in which all the gears shall be at 25 all times in mesh, with a view to obviating danger of stripping the teeth when the apparatus is thrown into service while the driving element is in motion.

A further object of my invention is to provide means for selectively locking the orbit gears of the planetary system that shall be characterized by its simplicity, by the absence of all slip, by its quickness of action 35 through the elimination of linkage, by the absence of wear, by the fact that in either of its operative positions it is self-locking, and by the fact that it needs only to be reversed when it is desired to operate the orbit gears in the opposite direction.

I also desire to provide a novel form of power transmitting mechanism especially designed for connection between a driving element and the reciprocating members of an 45 automatic stoker, whose nature shall be such as to permit of it being completely enclosed and perfectly lubricated, so that it is protected from accident or injury from foreign material such as dust, coal, etc., while at the

same time avoiding hazard to persons in its vicinity.

A still further object of my invention is to provide a power-box for a stoker drive comprising a slow-running heavy-duty spur-gear system adapted to stoker mechanism, a high-speed planetary gear-system, and means including a fracturable safety device for normally connecting the gear systems, the high-speed system including speed-control means.

Still another object of the invention is to provide a novel combination of parts particularly lending itself to the operation of a number of stoker rams from a single source of power, while obtaining the advantages above outlined.

These objects and other advantageous ends I attain as hereinafter set forth, reference being had to the accompanying drawings, in which,

Figs. 1 and 2 are respectively a front and a side elevation, the latter showing the crank shaft in section, and illustrating one form of my invention;

Fig. 3 is a plan of the apparatus shown in Figs. 1 and 2;

Fig. 4 is a vertical section on the line 4—4, Fig. 1;

Fig. 5 is an elevation, partly in vertical section, on the line 5—5, Fig. 1;

Fig. 6 is an elevation of the left side of the apparatus shown in Fig. 1;

Fig. 7 is a diagrammatic vertical section on the broken line 7—7, Fig. 2, illustrating the operative relations of the several gears;

Fig. 8 is a longitudinal vertical section, showing two transmitting units constructed and connected to a driving shaft, in accordance with my invention;

Fig. 9 is a diagrammatic vertical section similar to Fig. 7, and taken on the line 9—9, Fig. 13, illustrating a modification of my invention;

Fig. 10 is a front elevation of the internal gears and their associated cam;

Fig. 11 is a side elevation of one of the internal gears with the cam;

Fig. 12 is a perspective view of the cam and its spindle; and

Fig. 13 is a side elevational view of the modification shown in Fig. 9.

Referring first to Fig. 7, the spur-gear power-box embodying my invention comprises a casing or frame 1—1 which provides bearings for certain shafts, hereafter specified and which encloses the high and low speed gear trains and associated control means constituting important features of my invention. This casing is provided with 5 bearings for a sleeve or gear cage 2 having parallel arms in which is non-rotatably fixed a spindle 3. Within and keyed to the sleeve or planet-carrier is a tubular shaft 4 having a portion 5 at one end of said sleeve toothed to constitute a pinion. Journaled within the tubular shaft 4 is a driving shaft 6 actuated from any suitable source of power such as a motor or line of shafting as hereafter set forth. This last shaft within the casing is 10 formed or provided with a pinion 7 and is also journaled in a bushing 8 within the sleeve 2, being provided with suitable collars 9—9 to retain it in proper position.

The pinion 7 meshes with a planet gear 10 which constitutes one element of the high-speed gear system. The gear 10 is rotatably mounted on the spindle 3 and integrally or otherwise connected to a second planet gear 11, also on said spindle and having a different number of teeth. Both of the gears 10 and 11 are mounted between the arms of the sleeve 2 which carry the spindle 3 and are enclosed within a portion of the main casing structure constituting a chamber, within 15 which are rotatably mounted two internally toothed orbit gears 12 and 13 respectively meshing with said gears 10 and 11. These internal gears preferably operate side by side and are accessible through an opening in the casing normally closed by a cover plate 14, in which is journaled one end of the sleeve 2.

These internal gears 12 and 13 have their 20 adjacent edges recessed or formed with shoulders so that either of them may be gripped and held immovable by any suitable means such as a self-locking cam or eccentric member 15 mounted between them upon a short spindle 16 journaled in the casing structure 25. This spindle has fixed to its outer end an operating handle or lever 17 whereby it may be moved from a neutral position to one side or the other into gripping engagement with either of said internal gears.

The gear 5 on the sleeve 4 is preferably 30 mounted outside of the main casing 1—1, but within a housing or extension 18 thereof substantially concentric with the shaft 6, and meshes with a relatively wide faced gear 19 of comparatively large diameter loosely mounted on a hub 20 which is keyed or otherwise fixed to a shaft 21 journaled in the main casing structure so as to extend parallel with the shaft 6. This hub has bolted to it, concentric with the shaft, a plate 22 which may

be operatively connected to the gear 19 by a relatively weak and easily sheared safety pin 23 extending between a pair of suitably formed bushings mounted respectively in the plate and in said gear;—there being formed in the latter a passageway 24 into which one end of the pin may be easily moved after it has been broken by an excessive load and thereafter allowed to so escape.

A light cover 25 preferably encloses the 35 plate 22 and has projecting lugs or flanges extending into guideways 26, so that it is normally maintained in position. A suitable operating arm or bar 27 is mounted on the outside face of the cover 25, providing means whereby it may be rotated sufficiently to disengage its projecting lugs from the guideways 26 when it is desired to have access to the safety pin or others of the members adjacent thereto.

Mounted on the shaft 21 within the main casing structure are a pair of gears 30—30 which constitute elements of the slow-running heavy-duty spur-gear system. Both of these gears have the same number of teeth 40 and meshing respectively with a second pair of gears 31—31 fixed to opposite ends of a tubular shaft 32 rotatably mounted upon a relatively heavy spindle 33, non-rotatably fixed in the casing structure. Said tubular shaft 32, between the gears 31—31, has formed integral with it a pinion 34 meshing with a gear 35 which, like it, preferably lies in the central plane of the main casing structure.

This final gear 35 is fixed in any suitable manner to a shaft 36 also journaled in the casing structure and including one or more cranks 37. The latter are especially designed and adapted for the reception of connecting rods (not shown), whereby power is transmitted to the rams or pushers of an automatic stoker, and the gear 35, like the other moving parts of my apparatus, is completely enclosed in the present instance by a 45 cover structure 38.

Under conditions of operation, the shaft 6 is continuously driven by an electric motor or other source of power, thereby turning the 50 gear 7 and the two gears 10 and 11 on the shaft 3 as long as the operating handle 17 is in its neutral position. This rotation of the two gears 10 and 11 causes the internal gears 12 and 13 to turn at different speeds within the casing structure. If however said handle 55 be turned to one side of its neutral position its cam 15 will engage the shoulder of one of said gears, as for example the gear 12, causing it to be immovably held, whereupon the continued rotation of the gear 10 will cause it to move bodily with the sleeves 2 and 4 about the shaft 6, thereby turning the gear 5. Power is thus transmitted from said gear to the gear 19, thence through the shaft 21 to the gears 30, 31 and 34, to the gear 35, and 60 to the cover structure 38.

to the shaft 36 which is rotated at a speed depending upon the speed of the driving shaft 6 and the dimensions of the various gears above noted.

If the controlling handle 17 be so turned as to release the internal gear 12 and hold immovable the internal gear 13, power will be transmitted to the gear 5 through the smaller one of the planetary gears 11, with the result that the crank shaft 36 will be rotated at a speed less than that in the former case. Should an abnormal load be applied to the crank shaft, as would result from the jamming of one of the plungers or rams of the stoker, the safety pin 23 would be sheared off, thus disconnecting the gear 19 from the shaft 21 without doing injury to any of the parts of the device. The broken safety pin may be replaced by a new pin, after which, when the cause of the overload has been removed, the apparatus may be again put in operation.

From the above description it will be appreciated that not only are the moving parts so enclosed as to be effectually prevented from damage from dust and foreign bodies, but, by reason of the construction shown, they may be supplied with a lubricant such as a suitable grease or oil, which will maintain them in the best working condition. The possibility of injury to workmen from the power transmission gearing is practically eliminated and it is especially to be noted that the device throughout utilizes spur gearing for transmitting power from the driving to the driven members.

The arrangement is such moreover, that said gearing operates at relatively high efficiency, in one case about 70% and, as shown in Figs. 7 and 8, lends itself particularly to an arrangement wherein power is supplied to a number of transmitting units from a single source. In such case the shafts 6 of two such units are brought into substantial alignment and are connected by one or more lengths 40 of shafting through universal joints 41-41. These latter, as well as the connecting shaft 40, are preferably enclosed within a tubular casing 42 extending into the housing extensions 18 of the two transmitting units so that there are no exposed moving parts.

By the use of universal joints and connecting shaft it is possible to operably connect two units even though after connection they should change their relative positions by reason of foundation settling or expansion effects, due to the operation of the stokers with which they are associated.

In addition it is to be noted that at those points where severe stresses are developed under operating conditions, as in the supporting structure adjacent the crank- or driven shaft, the gears are so arranged as to be balanced, thereby avoiding in a large meas-

ure objectionable side or torsional stresses. As a consequence, liability of undue wear or breakage is avoided. Moreover by using planetary gearing in the combination shown, I am enabled to secure efficient and relatively large speed reduction between the driving and driven elements, while using a compact, simple and substantial combination of gears.

Under certain conditions, as when the gearing is not required to be so compact as in that form of my invention shown in Figs. 1 to 7, I may materially enlarge the diameter of the gear wheel 35a on the crank shaft and omit the intermediate gears 31-31, 34 and one of the gears 30, arranging the second gear 30 as shown in Fig. 9, so that it lies in the plane of and meshes with said gear 35a. In other particulars the construction of Fig. 9 is substantially that previously described, it being noted that in all cases I may employ either a single set of planetary gears or more than two such sets, without departing from my invention.

In that form of my invention shown in Fig. 9, as in that previously described, the gearing is so associated with the crank shaft and with the casing or frame in which the whole is supported that, as above pointed out, the side stresses on said frame and gearing are reduced to a minimum; the arrangement being balanced and for the most part subjecting the structure to compression or tension.

It is further to be noted that by using a cam 15 of the peculiar construction shown the device may be adapted with the utmost ease to suit operation of the internal gears in either direction. When the cam is arranged as shown in Figs. 4 and 10, for example, the internal gears 12 and 13 are designed to rotate in a counterclockwise direction. If however it is required that these with their associated parts should rotate in the opposite direction, it is obviously a simple matter to remove the supporting spindle with its cam and turn it through 180° so that when it is again mounted in the casing structure said cam may be moved to one side or the other to block a clockwise movement of the internal gears.

I claim:

1. The combination in a gear unit of driving and driven shafts; a train of gears connecting said shafts and including a plurality of orbit gears and a corresponding plurality of planet gears, the former including two adjacent gears having shoulders on their adjacent sides; with a cam mounted between said adjacent gears and movable at will into holding engagement therewith from a neutral position.

2. The combination in a gear unit of driving and driven shafts; a train of gears connecting said shafts and including a plurality of orbit gears and a corresponding plurality of planet gears, the former including two

adjacent gears each having two shoulders on their adjacent sides with a reversible cam mounted between said latter gears and movable at will into holding engagement with the shoulders thereof from a neutral position, said cam being formed to be capable of operatively coacting with one shoulder of each gear when the latter are turned in one direction and when reversed, of similarly coacting with the second shoulder of each gear.

3. A gear unit consisting of a supporting casing; a driving and a driven shaft; a driven planet carrier; a train of spur gearing connecting said shafts and including a plurality of revoluble orbit gears and a corresponding plurality of planet gears, the latter being mounted within the casing on said driven planet carrier; and means mounted between said orbit gears for gripping any one of them at will to prevent rotation thereof.

4. A gear unit consisting of a supporting casing; a driving and a driven shaft; a train of spur gearing connecting said shafts and including a plurality of planet gears and a plurality of cooperating orbit gears, said orbit gears including two rotatably mounted members supported adjacent to each other within the casing; a device mounted between said members for gripping either of them at will to prevent rotation thereof; and a handle for actuating said device.

5. A gear unit consisting of a supporting structure; a member rotatably mounted thereon and including a gear; a driven shaft actuated from said gear; a driving shaft coaxial with said member; a gear on said driving shaft; two gears having different numbers of teeth rotatably supported by said member and driven from the gear on the driving shaft; two internal gears rotatably mounted on the supporting structure and respectively engaged by the gears carried by said member; with a reversible cam for preventing rotation of either of the internal gears at will.

6. In combination, a supporting structure; a rotatable member journaled therein; a pair of planet gears on said rotatable member; a tubular shaft co-axial with said member; a driving shaft co-axial with said tubular shaft; a gear on said driving shaft for actuating said planet gears; a pair of orbit gears rotatably mounted on said supporting structure; and a cam operatively associated with said orbit gears so as to selectively lock the same.

7. Power transmission apparatus comprising a pair of orbit gears; a pair of shoulders individual to each gear; and a reversible locking member movable into engagement with one shoulder of each gear but when reversed movable into engagement with the remaining shoulders.

8. Power transmission apparatus comprising

ing a pair of orbit gears having spaced shoulders; and a self locking member movable from a neutral position intermediate said shoulders into engagement with one or the other of said shoulders.

9. Power transmission apparatus comprising a pair of orbit gears having adjacent faces recessed to form a pair of shoulders; and a self locking cam respectively movable into gripping engagement with said shoulders.

10. A stoker-drive power box comprising a variable speed gear train, said train including a pair of orbit gears for respectively determining the different speeds of said train; and a locking member positioned between said orbit gears for locking one or the other depending upon the desired speed of said train.

11. A power box comprising a drive shaft; a driven shaft; a train of spur gears permanently in mesh extending between said shafts; a pair of orbit gears operatively associated with said gear train and adapted when locked to control the speed thereof, said orbit gears having adjacent shoulders; and a locking member movable from a neutral position intermediate said shoulders into engagement with one or the other of the same.

12. A power-box comprising a high-speed system having orbit and planetary gears; a sun gear operatively connected with said planet gears, self-locking means movable into holding engagement with the desired one of said orbit gears for controlling the speed of said planetary gears.
